UNITED STATES PATENT OFFICE.

GEORGE F. CARD, OF COVINGTON, KENTUCKY, ASSIGNOR TO THE GEORGE F. CARD MANUFACTURING COMPANY, OF CINCINNATI, OHIO.

GOVERNOR FOR ELECTRO-DYNAMIC MACHINES.

SPECIFICATION forming part of Letters Patent No. 411,782, dated October 1, 1889.

Application filed October 29, 1888. Serial No. 289,384. (No model.)

To all whom it may concern:

Be it known that I, GEORGE F. CARD, a citizen of the United States, residing in Covington, in the county of Kenton and State of Kentucky, have invented a certain new and useful Improvement in Governors for Electro-Dynamic Machines, of which the following is a full, clear, and exact description.

My invention relates to governors for electric motors or dynamic machines arranged to automatically maintain a sensible uniform speed of armature rotation under changing loads, current forces, &c., and whose construction is, further, such as to promptly bring the armature to rest either upon its rotation dropping below a given range of velocities or upon a disablement of the centrifugal regulator.

My present invention is an improvement on the one shown and described in my pending application filed July 31, 1888, Serial No. 281,600.

In the accompanying drawings, forming part of this specification, Figure 1 is a top plan view of an electric motor with my governor attached. Fig. 2 is a side elevation of the same. Fig. 3 is a diagram to illustrate the paths respectively taken by the currents.

Supported upon any suitable base A is a field-magnet having several pairs of cores D, arranged in any convenient manner, upon which is wound the wire C of a normally-closed circuit which conveys the driving-current. Beside the said direct-winding field-cores one pair—say D' D', Fig. 3—are wound in the reverse direction, with a comparative low-resistance wire c, which forms a normally-open loop of the direct-winding wire, which, when closed, shunts part of the current in a direction opposite to the driving-current.

This shunt-circuit c is known as the "differential circuit." In the normal running condition of the machine this differential circuit is open and currentless and inert, but is capable of being automatically closed either by a speed of the armature in excess of the maximum velocity assigned to it or for which it is gaged, or by the opposite action of slowing down toward a stop; or also by the disorganization of the centrifugal mechanism of the governor itself. Whenever from either cause named

said differential circuit becomes the path of a current its reversely-directed windings tend to neutralize and, if maintained long enough, to even overpower the magnetism of the direct windings. The means employed by me for bringing said differential circuit automatically into action in the presence of either condition mentioned are as follows:

The short-circuit wire or loop diverges at some convenient point—say F—from the direct-winding wire to two normally-stationary terminals or contact-points G H. The contact-piece G consists, preferably, of a piece of carbon supported by a bracket I and movable in the clamp J. The wire may connect with the bracket I at any point, as the insulation at t cuts off the current from T or its connections, while the contact-piece H is supported on the bracket H'. The other end of the wire c, forming the loop or shunt circuit, is connected with the bracket I, supporting the shaft L. On the end of this shaft L is a pulley driven from the armature-shaft N by the belt N'.

O is a centrifugal regulator hinged at one end to the collar O' and at the other to the hub of the disk P. A spring R tends to bring the regulator to a collapsed condition. On the shaft L is a non-revolving collar or sleeve S, carrying a bracket S', which extends over and supports adjustably the carbon point T.

The terminal or contact point H consists of a bar supported by brackets H', the spring H'' tending to force it forward, within adjustable limits, into contact with the disk P, which moves backward or forward on and with the shaft L, its hub extending through the sleeve S.

The differential circuit is closed by the contact of the carbons G T or the disk P and point H. As the speed of the engine increases beyond the maximum fixed the centrifugal regulator O draws the collar S toward it, and with it the bracket S' and carbon T. As the carbon T comes in contact with the carbon G the differential circuit is closed, and the reverse current tends to neutralize the driving-current and reduce the speed of the engine, whereupon the centrifugal regulator becomes more relaxed and

the carbon T moves out of contact, opening the differential circuit. In practice the carbons do not actually part contact and entirely break the differential circuit unless the machine is overloaded; but as it begins to slow down the impact of the two carbons is lessened, producing a variable resistance by the changes of pressure. A still greater change of resistance is produced by the slight parting of the carbons, producing a short arc, so that within a very short space or limit of motion we have a variable resistance ranging from a pressing contact of the carbons to the actual or complete breaking of the circuit, thus securing very great delicacy of the regulator. The action of these parts is so delicate and prompt that the engine can be kept running at its maximum speed with great constancy and without any possibility of running away.

If the engine begins to slow down too much, the regulator O becomes more collapsed and the spring R forces the disk P into contact with the contact-point H, when the differential circuit is again closed and the driving-current neutralized and the engine entirely stopped. In case of any derangement of the centrifugal regulator from any cause the same action takes place, stopping the engine. In my application filed July 31, 1888, the general principles of my governor are shown. The arrangement, however, is less simple and effective. A single contact-point connected with the negative rheophore of the differential circuit vibrates between the two contact-points of the positive. In my present construction I have two pairs of contact-points. Where either contact-point is in motion the friction causes sparks, and is apt to cause irregular wearing of the surfaces and make the action less certain. I find, also, the pair of carbon points arranged to move to or from one another without rotation or other movement much more delicate and accurate and less dangerous of producing irregular and uneven contact-surfaces, as well as securing the variable resistance due to changes of pressure peculiar to carbon.

For adjusting the limit of speed I provide the gage U, which consists of a finger or pointer adjustable longitudinally in a slot by the thumb-screw U'. The carbon T is adjusted in the clamp S', so that it will come into contact with the point G when the disk P comes under the pointer or gage U. Should the carbons wear or burn away, so as to permit the disk P passing the pointer, they must be readjusted to keep the speed within the limit, which is done by means of the screw X,

which moves the brackets carrying the carbons G back or forward. The same screw is used for changing the speed of the machine by bringing the carbons nearer together or farther apart. The carbon T is of course insulated from the frame or bracket I, as indicated at t.

Having thus fully described my invention, what I claim, and desire to secure by Letters Patent, is—

1. The combination, in an electro-dynamic machine or motor, of the driving-circuit, the normally-open low-resistance differential circuit having two pairs of rheophores at its terminals, one of each pair of rheophores being movable and the other relatively stationary, the centrifugal speed-regulator, and connections between the same and the movable rheophores, whereby the respective pairs of rheophores will be caused to contact with variable degrees of pressure and thereby vary the resistance of the differential circuit when the speed of the dynamo becomes abnormal, substantially as described.

2. The combination, in an electro-dynamic machine or motor, of the driving-circuit, the normally-open differential circuit having the carbon rheophores at its terminals, one of which is movable, and the centrifugal speed-governor connected to the movable carbon rheophore, and thereby adapted to vary the resistance of the differential circuit at abnormal speeds, substantially as described.

3. In an electro-dynamic machine or motor, the combination of the armature, the centrifugal speed-governor revoluble synchronously therewith, the field-magnets having the differential circuit wound in the reverse direction to the drive-circuit, said differential circuit having the vibrating terminal connected to and operated by the governor, and the opposing relatively stationary terminals on opposite sides of the vibrating terminal, substantially as described.

4. In an electro-dynamic machine or motor, the combination of the centrifugal speed-governor, the field-magnets having the differential circuit wound in the reverse direction to the drive-circuit, said differential circuit having the vibrating terminal operated by the governor, and the opposing terminals on opposite sides thereof, and the gage to limit the play of the vibrating terminal, substantially as described.
